To all whom it may concern:

Be it known that I, FRANK. M. WINN, a citizen of the United States, residing at Salem, in the county of Essex and State of Massachusetts, have invented and produced a new and original Design for Bottles; and I do declare the following to be a full, clear, and exact description of the same, reference being had to the accompanying drawings, forming 10 a part thereof.

Figure 1 is a side elevation of a bottle showing my design; and Fig. 2 is a cross-section on the line 1—1 shown in Fig. 1.

Similar letters refer to similar parts wherever they occur on the different parts of the drawings.

The leading feature of my design consists of a bottle with a lower portion A, having a circular or curved circumference as shown and having an upper polygonal portion B above said curved portion A and immediately below the neck C as shown in the drawings.

What I wish to claim is—

The design for a bottle herein shown and described.

In testimony whereof I have affixed my signature in presence of two witnesses.

FRANK. M. WINN.
